UNITED STATES PATENT OFFICE.

WALTER H. D'ARDENNE, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

PUNCHING MACHINE.

Application filed March 8, 1921. Serial No. 450,573.

To all whom it may concern:

Be it known that I, WALTER H. D'ARDENNE, residing at Philadelphia, Pennsylvania, have invented certain new and useful 5 Improvements in Punching Machines, of which I declare the following to be a full, clear, and exact description.

This invention relates to improvements in 10 punching machines and has to do more particularly with automatic machines for 15 punching a plurality of holes at one operation in a sheet of metal.

One of the leading objects of my invention 15 is to provide a metal punching machine so constructed that it requires a very small amount of space above and at one side of the die or dies, so that it is capable of working on irregularly shaped stampings having portions which overhang the surface 20 to be perforated.

Another of the objects of my invention is 25 to provide a metal punching machine in which the punch, or punches, are carried by a rocking member, or members, so that the punch moves along a curved path in moving towards and from the die in which it works.

Another object of my invention is to provide a metal punching machine particularly 30 adapted to form a plurality of holes at one operation and capable of working on irregularly shaped stampings, having portions which overhang the dies, in which the punches are so actuated that they enter the metal successively thus lessening the maximum power requirement of the machine and 35 rendering it more efficient.

Another object of my invention is to provide a punching machine in which the punches are carried by a series of swinging 40 rock arms so arranged that the punches move towards the die along curved paths, the means for actuating the rock arms being such that they are actuated in different phase and the punches enter the metal successively so as to minimize the maximum 45 power requirement of the machine.

In the manufacture of automobile bodies, the rear portion of the body is frequently 50 formed by a curved tonneau panel, the lower side portions of which are pressed inwardly

so as to form inwardly extending wheel 55 housings. The upper wall of each wheel housing is curved and in some cases a series of holes are formed in this curved upper wall to receive the bolts for attaching the fender. One of the objects of my invention is to provide a punching machine in which the holes in the upper curved walls of the wheel 60 housings of a tonneau panel are punched at a single operation.

Further objects, and objects relating to 65 economies of material and details of construction, will definitely appear from the detailed description to follow: In one instance, I accomplish the objects of my invention by the devices and means described in the following specification. My invention is clearly defined and pointed out in the appended 70 claims. A structure constituting a preferred embodiment of my invention is illustrated in the accompanying drawing, forming 75 a part of this specification, in which:

Fig. I is a plan view of a machine embodying my invention showing a tonneau panel in place in the machine.

Fig. II is a longitudinal, sectional view 80 through the machine, taken on the line II—II of Fig. III, the tonneau panel being shown in section.

Fig. III is a view of the machine, partly 85 in plan and partly in section on the line III—III of Fig. II, the tonneau panel being removed.

Fig. IV is a vertical, sectional view taken 85 on the line IV—IV of Fig. II.

Fig. V is a sectional view taken on the line V—V of Fig. II.

Fig. VI is a view of the machine in end elevation.

Fig. VII is a detail, sectional view taken 90 substantially on the line VII—VII of Fig. VI.

Fig. VIII is a detail sectional view showing 95 one of the clamps and taken on the line VIII—VIII of Fig. III.

Fig. IX is an enlarged detail, sectional view, corresponding to a part of Fig. II and showing the engagement of a punch with the metal, and

Fig. X is a perspective view of the form 100

or type of tonneau panel on which the machine as illustrated is adapted to operate.

Similar reference numerals refer to similar parts throughout the several views, and the sectional views are taken looking in the direction of the arrows at the ends of the section lines.

In general, my invention contemplates a machine having a work-bed conforming generally to the surface to be perforated and in which the die or dies are mounted. Adjacent this work-bed, there are fulcrumed one or more swinging rock arms which carry one or more punches adapted to cooperate with said dies and arranged so that the punch moves in a curved path as it moves towards and from the die. This arrangement requires very little space above the die for the punch-carrying parts, so that the machine is particularly adapted for punching holes in irregularly shaped stampings, having portions which overhang the surface in which the holes are formed. Practically all of the punch-operating mechanism will be located on one side of the vertical plane through the dies, so that this machine is adapted for punching many irregularly shaped stampings or pieces which cannot be handled in other machines due to the location of the punch-operating parts with reference to the work-bed and dies. The rock arm or arms may be rocked by any suitable means, so as to cause the punches to move towards and from the dies, as, for illustration, through connections with a driven shaft, and, where there are a plurality of rock arms, I prefer to use driving connections such that the rock arms move in different phase so that the punches enter the metal successively. This distributes the strain and reduces the maximum power requirement of the machine. I have shown one illustrative form of driving connections for the rock arms, which functions in this manner, and which, in this instance, includes an eccentric on the driven shaft and a collar rotatably mounted on the eccentric and connected by links to the respective rock arms.

In this application, I show and describe a machine which is designed particularly for punching a series of holes, at one operation, in certain portions of a tonneau panel. In some automobile bodies, the rear portion of the body shell is formed by a curved tonneau panel and the side portions of this panel are pressed inwardly so as to give clearance for the wheels. These portions, which are pressed inwardly, are called wheelhousings and their upper walls are curved. This machine has work-beds so formed as to receive and support the upper walls of the wheelhousings, the tonneau panel being slid laterally into the machine and supported therein with said upper walls

of the wheelhousings resting on the work-beds. In this machine, there are two sets of punch-holders, one set for each wheelhousing, and the punch holders in each set are actuated so as to cause the punches carried by them to enter the metal successively and form a series of holes in the curved upper wall of the wheel housing. This is all done at a single operation. There may also be a series of holes to be formed in the side walls of the wheelhousings and I may do this, at the same operation, by providing laterally reciprocating punch holders which may be actuated from the same driven shaft as the swinging rock arms.

One embodiment of my invention is the machine illustrated in the drawings, which comprises a table, 10, carrying the upwardly extending heads, 11, at each end thereof. The inner walls of the heads, 11, may have the horizontal ledges, 12, formed thereon to support the bottom flanges of the tonneau panel. At the upper portions of these heads, 11, there are formed the curved work-beds, 13, in which a plurality of dies, 14, are mounted. These work-beds are curved so as to conform to those parts of the wheel housings which are to be perforated and which rest on them. Each head, 11, has an arm, 15, which extends forwardly from the work-bed, 13, as shown more particularly in Fig. VI. These arms, 15, have the vertically extending shoulders, 16 and 17, formed therein, against which the forward edges of the tonneau panel are clamped.

A drive shaft, 18, may be journaled in the bosses, 19, of the heads, 11, as shown in Fig. II. This drive shaft may also be journaled in the bosses, 21, formed on the frame members, 20, located between the two heads, 11. These frame members, 20, have a plurality of guide-ways, 22, formed therein, along lines radial to the axis of the shaft, 18, in which the push-rods, 23, are slidably mounted, being retained in place by the cover-plates, 24, closing the open sides of said guide-ways. On the frame members, 20, there are mounted a plurality of rocker arm holders, the bases, 25, of which are dove-tailed and fit in the dove-tailed grooves of the frame member, 20. There are shown three of these holders mounted on each frame member with the bases arranged so that they are substantially tangent with a circle concentric with shaft, 18. Each of these holders has a pair of parallel arms, 26, extending laterally from the base, and each pair of arms carries a pivot pin, 27, on which a rock arm, 28, is fulcrumed. Due to the arrangement of the rock arm holders on the frame member, these rock arms swing in planes containing the axis of shaft, 18, and each rock arm carries one or more punches, 29, which coact with corresponding dies, 14, carried by the work-bed. The

punches travel in curved paths due to the fact that they are carried by the swinging rock arms. The rock arms are so fulcrumed with reference to the dies, that the curved path of the punch is tangent to the axis of the corresponding die at a point a slight distance, in this case about one-sixteenth of an inch, below the top of the die, the horizontal plane containing the fulcrum axis of the arm lying slightly below the plane containing the point of contact of the punch with the metal when the punch is advanced to its work. As a result the punch engages the metal at a slight angle to the perpendicular and one edge of the punch enters the metal in advance of the other, as shown in Fig. IX. This gives a sort of shearing action and lessens the strain on the rock arms and other parts. The rear end of each rocker arm, 28, may be pivotally connected to the upper end of an idler link, 31, by a pin, 30, the lower end of said link being pivotally connected to the upper end of the push-rod, 23.

25 The shaft, 18, may have eccentrics, 32, formed thereon, in line with the push-rods, 23, and a collar, 33, is rotatably mounted on each eccentric. In order to provide connections with the push rods, these collars 30 may each have a flange, 33', and a vertically extending arm, 34. In the machine shown, the lower end of the central push-rod, 23, of each set, is pivotally connected by the pin, 35, to the upper end of the arm, 34.

35 The push-rods, 23, at each side of the central push-rod, may be connected to the flange, 33', by links, 53.

As I have indicated above, in some cases it is desirable to form a series of holes in 40 the side walls of the wheel housings. In Fig. VII, I have shown a mechanism for punching these holes. This comprises the dies, 36, which are positioned in the sides of the heads, 11, as shown, with respect to 45 one gang, in Fig. VII. A guide-way, 37, may be formed in the frame member, 20, and a push-rod, 38, slidably mounted in such guide-way, the open side of which may be closed by the cover-plate, 39. A horizontally extending guide-way, 40, may also be formed in the frame member, 20, and a 50 punch holder, 41, slidably mounted in this guide-way. The open side of this guide-way may be closed by the cover-plate, 42.

55 The punch-holder may carry a plurality of punches, 43, coacting with the dies, 36. This punch-holder may be actuated in various ways, for instance, by a toggle linkage, the rear link, 45, of which may be pivoted to 60 the frame member at 44, and the front link, 46, pivotally connected to the rear end of the sliding punch-holder, 41. The links, 45 and 46, are pivotally connected together and to the upper end of a tension link, 47, by 65 the pin, 48. A rocker link, 49, may be piv-

oted to the frame at 51. One end of the rocker link, 49, may be pivotally connected to the lower end of the tension link, 47, and the other end of said rocker link may be pivotally connected, at 52, to the upper end 70 of the push-rod, 38, the lower end of said push rod being connected to the collar flange, 33', by the link, 53. This provides a simple and efficient mechanism for reciprocating the punch holder, 41, along a line 75 parallel to the shaft, 18, from which it is driven.

It is desirable, of course, to provide various clamps so as to hold the tonneau panel firmly and rigidly in place in the machine during 80 the punching operation. I have shown certain clamping devices which I have used and have found to be very efficient in this machine, but it will be understood that other suitable clamping devices may be used if desired. In this machine I have provided a bracket, 54, on the frame member, 20, on which one end of the link, 55, is pivoted. A bell-crank lever, 56, is also pivoted to the bracket, 54, and a bent link, 57, has one end 90 connected, at 58, to one arm of the bell-crank lever, 56. The outer end of the link, 55, is pivotally connected to the link, 57, at the bend in the link. The outer end of the bent link, 57, has an enlarged boss, 60, in which a 95 stud, 61, may be adjustably mounted. This stud, 61, has a curved clamping block, 62, which conforms to the surface of the work-bed, 13, so as to clamp the wheel housing in place on the work-bed. This clamping device is shown in Fig. VIII and its location 100 on the frame is shown in Figs. I and III. By using the free end of the bell-crank lever, 56, as a handle, and swinging it to the left, in Fig. VIII, the toggle linkage, formed by 105 the other arm of the bell-crank lever and the link, 57, is broken and the clamping block swung back so as to permit the removal of the stamping. In the position shown in Fig. VIII, the parts are locked, due to the 110 toggle effect. I may also provide similar clamping devices which engage the front edges of the tonneau panel and clamp them against the shoulders, 16 and 17, of the arms, 115 15, projecting from the work-beds. This clamping device may comprise a bracket, 63, on which the bent link, 66, is pivotally mounted at 67. The free end of the link, 66, carries a stud, 65, which may be adjustably mounted therein, on which there is the clamping block, 64. A bell-crank lever, 68, is pivotally mounted at 69, on the end of the idler link, 70, which is pivotally connected 120 at 71 to the bracket, 62. The inner end of the bell-crank lever, 68, may be pivotally connected at 72, to the central part of the bent link, 66.

The shaft, 18, may be driven in any manner from any suitable source of power, but it is desirable that the drive be such that, 125

when it is disconnected, the swinging rock arms and sliding punch-holders will be removed from the work-bed so as to permit of the removal of the stamping. In the machine illustrated, I have provided a motor drive, so that the machine is self-contained, which drive includes a gear, 73, loosely mounted on the shaft, 18, and meshing with the pinion, 82, on the idler shaft, 83, which 5
10 idler shaft carries the gear, 84, meshing with the pinion, 85, on the shaft of the motor, 86. I have provided a clutch mechanism for controlling the driving connections of the shaft, 18, which clutch connection comprises 15
15 the clutch disc, 75, fixed on the shaft, 18, and carrying a sliding bevelled latch, 76, which is pressed in the direction of the gear, 73, by a spring, 77. The gear, 73, has a projecting part, or clutch pin, 74, extending toward the 20
20 clutch disc, 75, in position to engage the latch, 76, when the latter is projected, so as to drive the clutch disc from the gear, 73. A pivoted pawl, 78, is mounted so that its nose is in a position to engage the bevel of the latch, 76, to retract it, being normally held in such position by the spring, 78'. A link, 79, is connected to the pawl, 78, by which to withdraw it from the retracting 25
25 position against the tension of spring, 78', such link being actuated by the foot lever, 80. A spring-brake, 81, may act on the shaft, 18, so as to stop its rotation as soon as the drive is disconnected. This form of clutch is one which allows a complete rotation of the 30
30 shaft, 18, each time that the foot lever is depressed and the arrangement is such that the shaft is always stopped at the same point in its rotation. I am not, however, to be restricted to this particular form of clutch 35
35 connection, as there are many others which may be used with equal satisfaction in this mechanism.

In operation, the tonneau panel, A, is first inserted in the machine, with the lower 40 flanges, a', resting on the ledges, 12, of the heads, 11, and the upper curved walls, b', of the wheel housings resting on the curved work-beds, 13. The side walls, b, of the wheel housings are disposed against the 45 inner side faces of the heads, 11, below the curved work-beds, 13, as shown with respect to one of the wheel housings, in Fig. VII. The flanged forward edges of the tonneau panel, A, engage the shoulders, 16 and 17, of the forwardly extending arms, 15, and are clamped there by the clamp blocks, 64. The wheel housings are also clamped to the work-beds, 13, by the clamping blocks, 62. The operator then depresses the foot 50 lever, 80, and this action projects the clutch latch, 76, so that it is engaged by the clutch-pin, 74, of the gear, 73, and the driven shaft, 18, is carried forward through one revolution. This action causes the oscillation 55 of the respective swinging rock arms 60

so that each of the punches, 29, carried thereby, perforates the metal of the curved upper walls of the wheel housings. The punch holders, 41, are also reciprocated so that the punches, 43, pass through the side 70 walls of the wheelhousings. Due to the driving connections for the rock arms and the sliding punch holders, those at each end of the machine operate in different phase so that the punches carried by the respective rock arms and punch holders, enter the metal successively. The result is that the strain is distributed and the power required to operate the machine is not nearly so great as if all of the punches entered the 80 metal at the same time. Furthermore, the dies, 14, are so set in the curved work-bed, 13, that one edge of the punch engages the metal slightly in advance of the other. This is due to the fact that the axis of the die is 85 tangent to the curved path of the punch at a point a very slight distance below the top of the die, so that the punch enters the die at a very slight angle. This gives a shearing action to the punch which helps to relieve the strain on the machine. As soon as the shaft, 18, completes one revolution, the foot lever being released, the pawl, 78, is in position so that it retracts the latch, 76, as soon as the latter comes into engagement with it. As a result, the drive is disconnected at the end of the revolution of the shaft, and the spring-brake, 81, stops the shaft at once so as to hold the punch-holders and rock arms in their withdrawn position. 90

I am aware that the particular machine which I have disclosed in this application, may be changed considerably without departing from the spirit of my invention, and, therefore, I claim my invention broadly, 105 as well as specifically, as indicated by the appended claims.

Having thus described my invention, what I claim as new and useful in my invention, and desire to secure by Letters Patent is:

1. A machine of the class described comprising a stationary bed on which the part to be punched rests, a swinging rock arm, a punch carried thereby and co-operating with said bed, and means for oscillating said swinging rock arm to cause said punch to move in a curved path to and from said bed, the axis about which said arm swings lying in a horizontal plane below the plane 115 of contact of the punch with the work.

2. A machine of the class described comprising a stationary bed on which the part to be punched rests, a die carried by said bed, a swinging rock arm having a fixed 125 pivot at one side of said die and disposed in a horizontal plane below the plane of contact of the punch with the work, a punch carried thereby, said die being disposed in relation to said punch to co-operate there- 130

with when said arm is rocked, and means for oscillating said swinging rock arm to cause said punch to move in a curved path to and from said die.

5. 3. A machine of the class described comprising a stationary bed on which the part to be punched rests, a die carried by said bed, a swinging rock arm having a fixed pivot and constituting a lever of the first 10 order, a punch carried thereby, said die being disposed in relation to said punch to co-operate therewith when said arm is rocked, and means for oscillating said swinging rock arm to cause said punch to move in a curved path to and from said die.

4. A machine of the class described comprising a bed on which the part to be punched rests, a die carried by said bed, a frame member, a swinging rock arm pivoted therein with one end thereof overhanging the die, a punch carried by the overhanging end of said rock arm, said die being disposed in relation to said punch to co-operate therewith when said arm is 20 rocked, and means for oscillating said swinging rock arm to cause said punch to move in a curved path to and from said die, said rock arm being pivoted in the frame in a horizontal plane below the plane 25 of contact of the punch with the work.

5. A machine of the class described comprising a bed on which the part to be punched rests, a die carried by said bed, a frame member, a swinging rock arm pivoted therein with one end thereof overhanging the die, a punch carried by the overhanging end of said rock arm, said die being disposed in relation to said punch to co-operate therewith when said arm is 30 rocked, a push rod connected to said rock arm and confined to reciprocating motion in a straight line, and means for reciprocating said push rod.

6. A machine of the class described comprising a bed on which the part to be punched rests, a die carried by said bed, a frame member, a swinging rock arm pivoted therein with one end thereof overhanging the die, a punch carried by the overhanging end of said rock arm, said die being disposed in relation to said punch to 40 cooperate therewith when said arm is rocked, a push rod, means to confine said rod to longitudinal movement, a link connecting said push rod and said rock arm, and means for reciprocating said push rod.

7. A machine of the class described comprising a bed on which the part to be punched rests, a die carried by said bed, a frame member, a swinging rock arm pivoted therein with one end thereof overhanging the die, a punch carried by the overhanging end of said rock arm said die being disposed in relation to said punch to 50 cooperate therewith when said arm is 55

rocked, a push rod connected to said rock arm, means to confine said rod to longitudinal movement, a driven shaft, an eccentric on said shaft, and means for reciprocating said push rod from said eccentric.

70

8. A machine of the class described comprising a bed on which the part to be punched rests, a die carried by said bed, a frame member, a swinging rock arm pivoted therein with one end thereof overhanging the die, a punch carried by the overhanging end of said rock arm said die being disposed in relation to said punch to co-operate therewith when said arm is rocked, a push rod connected to said rock arm, a driven shaft, an eccentric on said shaft, and a collar within which said eccentric is rotatably mounted and to which said push rod is connected.

75

9. A machine of the class described comprising a bed on which the part to be punched rests, a die carried by said bed, a frame member, a swinging rock arm pivoted therein with one end thereof overhanging the die, a punch carried by the overhanging end of said rock arm and cooperating with said die, a push rod connected to said rock arm, means to confine said rod to longitudinal movement, a driven shaft, an eccentric on said shaft, a collar within which 85 said eccentric is rotatably mounted, and a link connecting said push rod and said collar.

80

10. A machine of the class described comprising a bed on which the part to be punched rests, a die carried by said bed, a swinging rock arm, a punch carried thereby and cooperating with said die, said rock arm being so positioned with respect to said die that one edge portion of said punch engages the metal in advance of the remaining edge portions, and means for oscillating said swinging rock arm to cause said punch to move in a curved path to and from said die.

100

11. A machine of the class described comprising a curved work-bed, a frame member, a plurality of swinging rock arms pivoted on said frame member, said rock arms being so positioned that they oscillate in planes substantially radial to the curved work-bed, and means for oscillating said rock arms.

115

12. A machine of the class described comprising a work-bed adapted to receive and position the work in the machine, a plurality of swinging rock arms, punches carried by said rock arms and cooperating with the work-bed to punch work positioned thereon, a rotating drive shaft, said swinging rock arms being mounted to oscillate in planes substantially radial to said shaft, and connections between said shaft and the rock arms for oscillating the latter.

120

13. A machine of the class described comprising a curved work-bed on which the part 130

125

- 6 to be punched rests, a plurality of swinging rock arms, punches carried thereby and co-operating with said work-bed, the pivotal axes of said rock arms being so disposed 5 with relation to the work-bed that the punches engage the metal on the work-bed at a slight angle from the perpendicular, and means for oscillating said rock arms.
14. A machine of the class described comprising a curved work-bed on which the part to be punched rests, a plurality of swinging rock arms, punches carried thereby and co-operating with said work-bed, said rock arms being so pivoted that the punches engage the 10 metal on the work-bed in advance of a horizontal position of said arms and at a slight angle from the perpendicular, and means for oscillating said rock arms in a predetermined sequence.
15. A machine of the class described comprising a curved work-bed, a frame member, a plurality of rock-arm carriers mounted on said frame member, a swinging rock arm pivoted on each carrier, punches carried by 15 said rock arms and cooperating with said work-bed, said carriers being so positioned that the rock arms oscillate in planes substantially radial with respect to the curved work-bed, and means for oscillating said 20 rock arms.
16. A machine of the class described comprising a work-bed, a plurality of pivotally mounted swinging rock arms, punches carried by said rock arms and cooperating with 25 said work-bed, a driven shaft, and means for oscillating said rock arms from said driven shaft, the pivotal axes of said rock arms being located nearer said shaft than are the 30 points of initial contact of the punches with the work carried by the work-bed.
17. A machine of the class described comprising a work-bed, a plurality of swinging rock arms, punches carried by said rock arms and cooperating with said work-bed, a driven shaft, and means for oscillating said 35 rock arms from said driven shaft in a predetermined sequence.
18. A machine of the class described comprising a curved work-bed, a plurality of pivotally mounted swinging rock arms, punches carried by said rock arms and co-operating with said work-bed, a driven rotating shaft having its axis substantially coincident with the axis of the curved work-bed, and means for oscillating said rock 40 arms from said driven shaft.
19. A machine of the class described comprising a curved work-bed, a plurality of swinging rock arms, punches carried by said rock arms and cooperating with said work-bed, a driven shaft having its axis substantially coincident with the axis of the curved work-bed, and means for oscillating said rock 45 arms from said driven shaft in a predetermined sequence.
20. A machine of the class described comprising a curved work-bed, a driven rotating shaft having its axis substantially coincident with that of the curved work-bed, a plurality of pivotally mounted rock arms swinging in planes radial with respect to the axis of said shaft, punches carried by said rock arms and co-operating with said work-bed, and means for oscillating said rock arms from said driven shaft. 70
21. A machine of the class described comprising a curved work-bed, a plurality of swinging rock arms, punches carried by said rock arms and co-operating with said work-bed, a driven shaft, a plurality of push-rods connected to said rock arms, guiding means in which said push-rods are mounted to slide longitudinally and means for reciprocating said push-rods from the driven shaft. 75
22. A machine of the class described comprising a curved work-bed, a plurality of swinging rock arms, punches carried by said rock arms and co-operating with said work-bed, a driven shaft, a plurality of push rods, guiding means in which said push rods are 80 mounted to slide longitudinally, links connecting said push rods and the rock arms, and means for reciprocating said push rods from the driven shaft. 85
23. A machine of the class described comprising a curved work-bed, a plurality of swinging rock arms, punches carried by said rock arms and co-operating with said work-bed, a driven shaft, a plurality of push rods, guiding means in which said push rods are 90 mounted to slide longitudinally, links connecting said push rods and the rock arms, an eccentric on said shaft, and means for reciprocating said push rods from the driven shaft. 95
24. A machine of the class described comprising a curved work-bed, a plurality of swinging rock arms, punches carried by said rock arms and co-operating with said work-bed, a driven shaft, a plurality of slidably mounted push-rods, links connecting said 100 push rods and the rock arms, an eccentric on said shaft, and a collar in which said eccentric is rotatably mounted and to which said push rods are connected. 105
25. A machine of the class described comprising a curved work-bed, a driven shaft having its axis substantially coincident with that of the curved work-bed, a plurality of rock arms swinging in planes radial to the axis of said shaft, punches carried by said 110 rock arms and coacting with said work-bed, a plurality of slidably mounted push-rods, links connecting said push rods and the rock arms, an eccentric on said shaft, and a collar in which said eccentric is rotatably mounted 115 and to which said push rods are connected. 120
26. A machine of the class described comprising a work-bed, a plurality of pivotally mounted swinging rock arms, a laterally-reciprocating punch-holder, punches respec- 125 130

- tively carried by said rock arms and punch-holder and cooperating with said work-bed and a common means for actuating said rock arms and punch holder.
27. A machine of the class described comprising a work-bed, a driven shaft, a plurality of pivotally mounted swinging rock arms, a laterally reciprocating punch-holder, punches respectively carried by said rock arms and punch-holder and cooperating with said work-bed, and means for actuating said rock arms and punch holder from said driven shaft. 70
28. A machine of the class described comprising a work-bed, a driven shaft, a plurality of swinging rock arms, a laterally reciprocating punch-holder, punches carried by said rock arms and punch-holder and cooperating with said work-bed, and means for actuating said rock arms and punch-holder in a predetermined sequence from said driven shaft. 80
29. A machine of the class described comprising a curved work-bed, a driven shaft having its axis substantially coincident with that of said work-bed, a plurality of rock arms swinging in planes radial to the axis of said shaft, a punch-holder mounted to reciprocate along a line parallel to the axis of said shaft, and means for oscillating said rock arms and reciprocating said punch holder from said driven shaft. 85
30. A machine of the class described comprising a curved work-bed, a driven shaft having its axis substantially coincident with that of said work-bed, a plurality of rock arms swinging in planes radial to the axis of said shaft, a punch-holder mounted to reciprocate along a line parallel to the axis of said shaft, and means for oscillating said rock arms and reciprocating said punch holder from said driven shaft in a predetermined sequence. 90
31. A machine of the class described comprising a work-bed, a driven shaft, a plurality of pivotally mounted swinging rock arms, a laterally moving punch-holder, punches respectively carried by said rock arms and punch-holder and cooperating with said work-bed, an eccentric on said shaft, and means for oscillating said rock arms and reciprocating said punch holder from said eccentric. 100
32. A machine of the class described comprising a curved work-bed, a driven shaft having its axis substantially coincident with that of said work-bed, a plurality of rock arms swinging in planes radial to the axis of said shaft, a punch holder mounted to reciprocate along a line parallel to the axis of said shaft, an eccentric on said shaft, and means for oscillating said rock arms and reciprocating said punch holder from said eccentric in a predetermined sequence. 110
33. A machine of the class described comprising a table, work supporting members at each end of the table, each having a curved work-bed, a driven shaft, a set of punch-holders for each work-bed, punches carried thereby and respectively cooperating with said work-beds, and connections with said shaft for actuating the punch holders of both sets simultaneously. 120
34. A machine of the class described comprising a table, work supporting members at each end of said table, each having a curved work-bed, a driven shaft, a set of punch holders cooperating with each work-bed, and connections between said driven shaft and both sets of punch holders for actuating the punch holders of each set in a predetermined sequence. 125
35. A machine of the class described comprising a table, work supporting members at each end of said table, each having a curved work-bed, a driven shaft, a gang of pivotally mounted swinging rock arms for each work-bed, punches carried thereby and respectively cooperating with said work-beds, and means for oscillating the rock arms of each gang from said driven shaft. 130
36. A machine of the class described comprising a table, work supporting members at each end of said table, each having a curved work-bed, a driven shaft, a set of swinging rock arms for each work-bed, each carrying punches cooperating with said work-bed, and means for oscillating said rock arms from said shaft so that the rock arms of each set move in a predetermined sequence. 135
37. A machine of the class described comprising a table, work-supporting members at each end of said table, each having a curved work-bed, a driven shaft having its axis substantially coincident with that of the curved work-beds, a set of swinging rock arms for each work-bed, each carrying punches cooperating with said work-beds, and means for oscillating said rock arms from said shaft so that the rock arms of each set move in a predetermined sequence. 140
38. A machine of the class described comprising a table, work-supporting members at each end of said table, each having a curved work-bed and a substantially vertical shoulder in front of said work-bed, means for clamping the work to said shoulders, and a plurality of punches cooperating with said work-beds. 145
39. A machine of the class described comprising a table, work-supporting members at each end of said table, each having a curved work-bed, means for clamping a tonneau panel in place on said work-supporting members with the upper walls of the tonneau wheel housings resting on said curved work-beds, and a plurality of punches cooperating with said work-beds. 150
40. A machine of the class described comprising a table, work-supporting members

at each end of said table, each having a curved work-bed and a horizontal ledge below said work-bed, means for holding a tonneau panel on said work-supporting members with its lower side edges resting on said ledges and the upper walls of the tonneau wheelhousings resting on said curved

work-beds, a plurality of punches cooperating with said work-beds, and means for actuating said punches.

10

In testimony whereof, I affix my signature.

WALTER H. D'ARDENNE.
